UNITED STATES PATENT OFFICE

JACKSON P. BROWN, OF MONTOURSVILLE, PENNSYLVANIA

CAP FOR THE BREATHER PIPES OF INTERNAL COMBUSTION ENGINES

Application filed June 18, 1931, Serial No. 545,306. Renewed March 25, 1933.

This invention relates to a cap for the breather pipe of an internal combustion engine, and has for one of its objects to provide a device of this character which shall 5 be adapted to utilize the current of air generated by the cooling fan to effect the withdrawal of vapors from the crank case, which shall be adapted to prevent the oil from being discharged from the crank case by way 10 of the breather pipe, and which shall be adapted to be readily removed from the breather pipe to permit the refilling of the crank case.

With the foregoing and other objects in 15 view, the nature of which will appear as the description proceeds, the invention consists in the construction, combination and arrangement of parts hereinafter fully described and claimed, and illustrated in the 20 accompanying drawing, wherein:—

Figure 1 is a view in side elevation of an internal combustion engine having its breather pipe equipped with a cap constructed in accordance with my invention.

Figure 2 is a top plan view of the cap, and

Figure 3 is a sectional view taken on the line 3—3 of Figure 2.

Referring in detail to the drawing, 1 30 designates the cylinder block, 2 the crank case, 3 the breather pipe, and 4 the cooling fan of a conventional internal combustion engine.

The cap for the breather pipe, which is 35 generally designated 5, comprises a hollow body 6 and a hollow attaching member 7. The body 6 is closed at its front end and fully open at its rear end, and the attaching member 7 extends downwardly from the body at a point close to the front end of the latter. The front end portion of the body 6 is of conical formation, as shown at 40 6a, and the body gradually increases in diameter from its front end portion to its rear end. The attaching member 7 which is 45 fully open at its ends is in full communication at its upper end with the interior of the body 6, and decreases in diameter from its upper to its lower end. The cap 5 is 50 applied to the breather pipe 3 by inserting

the attaching member 7 in the upper end of the breather pipe. As the attaching member 7 tapers downwardly, it may be easily inserted in the breather pipe 3, and it will wedge therein sufficiently to prevent the accidental displacement of the cap. As the attaching member 7 extends downwardly from the body 6, the insertion of the attaching member in the breather pipe 3 positions the body above the breather pipe. The cap 5 is applied to the breather pipe 3 in a manner to position its body 6 in the path of and longitudinally with relation to the current of air generated by the fan 4, and also in a manner to position its closed conical end portion 6a facing the current of air. The air flows about the body 6 from the front closed end thereof to and pass the rear open end thereof, with the result that the suction is produced at the rear open end 70 of the body which draws vapors from the crank case 2.

As the front end of the body 6 is closed, as the front end portion 6a is of conical formation, and as the body increases in diameter from its front end portion to its rear end, it offers little resistance to the air current and causes the air current to produce a strong action at its rear end. The body 6 occupies an upwardly and rearwardly inclined position with relation to its attaching member 7 and to the breather pipe 3, with the result that any oil forced into the body is returned to the crank case 2, 80 with the result that comparatively little or no oil will be lost through the breather pipe. The cap is simple, may be made from sheet metal and of different sizes for application to breather pipes of different sizes, 85 and it may be manufactured and sold at a comparatively low cost.

While I have described the principle of the invention, together with the structure which I now consider the preferred embodiment thereof, it is to be understood that the structure shown is merely illustrative and that such changes may be made, when desired, as fall within the scope of the invention as claimed.

What is claimed is:—

A cap for the breather pipe of an internal combustion engine, comprising a hollow body closed at its front and open at its rear end and provided in its lower side with an opening, the front end portion of the body being of conical formation and,

the body increasing in diameter from its front end portion to its rear end, and means for securing the body to the breather pipe in an upwardly and rearwardly inclined position thereon and with its bottom opening in registration with the breather pipe.
